UNITED STATES PATENT OFFICE.

RICHARD J. ROGERS, OF CHELSEA, MASSACHUSETTS, ASSIGNOR OF TWO-THIRDS TO ALONZO B. ROGERS, OF SAME PLACE, AND JOHN M. BYRON, OF BOSTON, MASSACHUSETTS.

OSCILLATING WATER-METER.

SPECIFICATION forming part of Letters Patent No. 373,608, dated November 22, 1887.

Application filed August 6, 1887. Serial No. 246,264. (No model.)

To all whom it may concern:

Be it known that I, RICHARD J. ROGERS, of Chelsea, in the county of Suffolk and State of Massachusetts, have invented certain new and useful Improvements in Water-Meters, of which the following, taken in connection with the accompanying drawings, is a specification.

My invention relates to meters for measuring fluids under pressure, and to that class of such meters as are usually termed "piston meters;" and it consists in certain novel features of construction, arrangement, and combination of parts, which will be readily understood by reference to the description of the drawings and to the claims to be hereinafter given, and in which my improvements are particularly pointed out.

Figure 1 of the drawings is a vertical longitudinal section through the outer casing, and showing the measuring-cylinder and other working parts in elevation. Fig. 2 is a longitudinal section of the working-cylinder and a portion of the outer casing on line *x x* on Fig. 1, and showing the remainder of the lower section of said casing in plan, the upper section or cover being removed. Fig. 3 is a transverse section on line *y y* on Figs. 1 and 2. Fig. 4 is a transverse section on line *z z* on Figs. 1 and 2, and Fig. 5 is an end view of the bar or yoke connecting the locking-spindles.

In the drawings, *A* is the outer casing, made in two parts, each provided with a horizontal flange, by which and suitable bolts said two parts are firmly secured together, the line of division being above the center of the same, as shown.

B is the measuring-cylinder, provided with the trunnions *a* and *b*, the valve-chambers *c* and *d*, the exhaust-passages *e* and *e'*, leading, respectively, from the chambers *c* and *d* to the interior of the trunnion *a*, and the ports *f* and *f'*, leading, respectively, from the chambers *c* and *d* to the interior of the cylinder *B* at opposite ends thereof, as shown in Fig. 2.

C is the piston, fitted to reciprocate in said cylinder *B* and made of greater weight than the same bulk of water, for a purpose which will presently appear. The cylinder *B* is mounted by its trunnions in half-boxes *g g*,

projecting inward from the vertical wall of the lower section of the casing *A*, as shown in Figs. 2, 3, and 4. The trunnion *a* has screwed into it the discharge-pipe *D*, and the trunnion *b* has screwed into it the stem *E*, upon which may be mounted a lever (not shown) for operating the register, (also not shown.)

The casing *A* is provided with the stuffing-box *F*, to pack the discharge-pipe *D*, and the stuffing-box *F'*, to pack the stem *E* and prevent leakage around the same, and has cast upon its under side the feet *A' A'*, to support it in a horizontal position, and water is admitted thereto through the pipe *G*. (Shown in Figs. 3 and 4.)

The valve-chambers *c* and *d* are each provided with two valve-seats, as shown at *c'* and *c''* in Fig. 3, with which the inlet-valve *c'* and exhaust or discharge valve *c''* respectively engage alternately as the cylinder *B* is vibrated about its axis of oscillation, said valves being firmly secured upon the valve-stem *h*, which is fitted to a bearing, *h'*, formed in the upper part of the chamber *c* or *d*, while the piston-like valve *c''* is guided in a bearing in the lower end of said chamber *c* or *d*, the ends of said valve stem *h* abutting against the lugs or shoulders *i* and *i'* formed, respectively, in the upper and lower portions of the casing *A*, all as shown in Fig. 3.

In the center of each of the heads *B'* of the cylinder *B* is mounted so as to be movable endwise therein a pin, *j*, which has formed upon its outer end a head, *j'*, in which are formed the two grooves *j''* to receive the forked ends of the bar or yoke *H*, the end portions of which are bent at right angles to the main body and forked, as shown in Fig. 5, the bar *H* being fitted to bearings *k k* on the cylinder *B*, all so constructed and arranged that when the piston *C* is moved in the direction indicated by the arrow on Fig. 2 and approaches the end of its movement in that direction it will strike the pin *j* in the right-hand head of the cylinder *B* and move it outward until said piston strikes the hub on the inner side of said head, and at the same time, through the medium of the bar *H*, will move the pin *j* in the head at the left-hand end of said cylinder inward

an equal distance and disengage it from the locking-lever J and cause the leather packing-ring l on said pin to pack the joint around said pin and prevent leakage around the same.

- 5 I I are two stands secured to the lower section of the case A, one at each end, to the upper end of each of which is pivoted the pendent locking-latch J, the shoulder m of which engages with the upper surface of the head j' of the pin j, as shown at the left of Fig. 1, to lock the cylinder in the position with its left-hand end depressed, as shown in Fig. 1.
- The operation of my invention is as follows: The parts being in the positions shown in the drawings and the casing being filled with water under pressure, if the faucet be opened to draw water therefrom, water will enter the valve-chamber d beneath the inlet-valve c' at the left of Fig. 1, and, flowing through the port f' 15 into the cylinder B, will move the piston C toward the right-hand end of the cylinder B until said piston comes in contact with the hub of the right-hand head B', having in so doing moved the pins j j and bar H in the same direction, and thereby withdrawn the head j' of the pin j at the left of Fig. 1 from beneath the locking-lever J, when the excess of weight in the right-hand end of the cylinder will cause that end thereof to be depressed until the locking-lever J at the right of Fig. 1 engages with the head j' of the pin j and locks said cylinder in that position. At the commencement of the operation the inlet-valve c' at the left and the exhaust-valve c' at the right of Fig. 1 were 20 open and the other two valves were closed; but the depressing of the right-hand end of the cylinder causes the closing of the left-hand inlet and the right-hand exhaust or discharge valves and the opening of the right-hand inlet 25 and the left-hand exhaust or discharge valves, when the water will enter the right-hand end of the cylinder through the valve-chamber c and the passage f to move the piston C toward the left again, the water in said cylinder at 30 the left of the piston passing through the part

f' into the chamber d, thence between the seat c' and the valve c' at the right of Fig. 1 to the lower part of said chamber d, thence along the passage e to the interior of the trunnion a, and thence through pipe D to the faucet. These 50 operations will be repeated as long as the faucet remains open.

What I claim as new, and desire to secure by Letters Patent of the United States, is—

1. In a water-meter, the combination of an 55 oscillating cylinder provided with independent valve-chambers for each end thereof, a piston of greater specific gravity than water, arranged to move endwise in said cylinder, and an inlet and discharge valve in each of 60 said valve-chambers, both mounted in fixed positions on a valve-stem and arranged to be alternately opened and closed by the vibration of the cylinder, the inlet-valve being opened and the discharge-valve closed at one end of 65 said cylinder and the discharge-valve being opened and the inlet-valve closed at the other end of the cylinder by the same movement of the cylinder.

2. In a water meter, the combination of a 70 fixed water chamber or reservoir provided with a water-supply pipe, an oscillating cylinder mounted in said reservoir and provided with independent valve-chambers for each end thereof, a piston of greater specific gravity 75 than water, arranged to move endwise in said cylinder, and an inlet and discharge valve in each of said valve-chambers, both mounted in fixed positions on a valve-stem, all arranged and adapted to operate substantially as and 80 for the purposes described.

In testimony whereof I have signed my name to this specification, in the presence of two subscribing witnesses, on this 2d day of August, A. D. 1887.

RICHARD J. ROGERS.
